(57) **CLAIM**

The ornamental design for a respiration mask with filter holder and parts thereof, as shown and described.

DESCRIPTION

FIG. 1 is a front perspective view of a respiration mask with filter holder and parts thereof, showing our new design;

FIG. 2 is a rear perspective view thereof;

FIG. 3 is a front elevational view thereof;

FIG. 4 is a right side elevational view thereof, the left side elevational view being a mirror image thereof;

FIG. 5 is a rear elevational view thereof;

FIG. 6 is a top plan view thereof; and,

FIG. 7 is a bottom plan view thereof.
